(57) **CLAIM**

The ornamental design for a screen for hospital beds, as shown and described.

DESCRIPTION

1. Screen for hospital beds

1.1: Front perspective

1.2: Front elevation

1.3: Top perspective

1.4: Bottom perspective

1.5: Rear perspective

1.6: Bottom plan

1.7: Front perspective

1.8: Right side elevation

1.9: Rear perspective

1.10: Top perspective

The design relates to mobile screens which are collapsible and expandable, and which are intended for placement at the head side of beds and gurneys; reproductions 1.1 to 1.6 show the expanded state of the screen; reproductions 1.7 to 1.10 show the collapsed state of the screen.

1 Claim, 10 Drawing Sheets
